UNITED STATES PATENT OFFICE.

CHARLES A. STICH, OF NEW YORK, N. Y.

SHEARING AND PUNCHING MACHINE.

1,259,801.

Specification of Letters Patent. Patented Mar. 19, 1918.

Application filed November 3, 1916. Serial No. 129,257.

To all whom it may concern:

Be it known that I, CHARLES A. STICH, a citizen of the United States of America, residing at West New Brighton, New York, 5 N. Y., have invented new and useful Shearing and Punching Machines, of which the following is a specification.

The invention relates particularly to improvements in machines for punching and 10 shearing plates, bars or other shapes of iron or other metal.

The main object is to obtain a maximum amount of power by a single operation. Another object is to provide a hand power machine which can be operated by one or two operators from either or both sides of the machine. Another object is to provide a machine which can be readily converted from a hand power machine to one driven 20 by a belt or motor by simply substituting gears and fly-wheel for the hand levers but without altering the general construction of the machine. Another object is to provide a machine which can be turned in any direction 25 whether operated by hand or driven by a belt or motor.

The invention in its preferred form has a vertically movable gate or head operated by a special system of hand levers and toggles to punch or shear plates, rods or bars. Secondary slides operated by the head are adapted to cut right and left handed angles. One operating handle is located on each of 30 two opposite sides of the machine so that the head can be operated by either handle from either side. By suitable interlocking devices both handles may be operated simultaneously. The main body or framework and operating mechanism are mounted on a 35 turn-table so that the machine may be turned in any direction toward the work. By substituting a set of gears for the hand levers the machine may be driven by a belt or motor, and still turn in any direction 40 without interfering with the application of power.

Figure 1, is a rear projection and partial vertical section of the entire machine showing the operating parts retracted or lifted 50 and the ends of the operating handles broken off.

Fig. 2, is a similar front view of the left hand half of a machine and showing the right hand half only partly exposed.

55 Fig. 3, is a vertical sectional view on the plane of the line 3—3 of Fig. 1.

Fig. 4, is a horizontal section and plan on the plane of the line 4—4 of Fig. 1.

Fig. 5, is a fragmentary section on the plane of the line 5—5 of Fig. 1. 60

Fig. 6, is a fragmentary section on the plane of the line 6—6 of Fig. 2.

Figs. 7 to 15 inclusive are perspective views of some of the movable parts.

Figs. 16 and 17 are perspective views of 65 the crank shaft and connecting rod to be used when the machine is driven by belt or motor.

Figs. 18 and 19 are two vertical projections of the gear constructions necessary for 70 driving the machine by belt or motor.

The main frame of the machine consists of the plates *a a'* together with the brackets *b b* and the main side plates *b' b'*.

An operating lever *c* is hinged on each 75 bracket and connected by a link *d* to an arm *e*. The shaft *f* is carried by the side plates *b' b'* and carries crank eccentrics *f' f'* connected to the levers *e e*. The arm *e* is provided with a hook *e'* engaging under a hook *f'* on the eccentric so as to couple the parts together when the arm *e* is moved to the left as shown in Fig. 1. A rod *e''* is provided for coupling the arm *e* and the eccentric *f'* positively. This rod *e''* may be moved in and out 85 by a rack and pinion *e''* and the handle *e''*. A stationary stop *e''* may be provided on the main frame for the arm *e*. Each eccentric *f'* is connected by a rod *g* to a socket in the slide *h*. A cap piece *h'* rigidly connects the 90 opposite upper ends of the sides of the slide *h*. Links *i* and *j* are hinged at each edge of the slide *h*. Toggle *k* is swung on stationary stud *l* carried by the main frame and has its lower end seated in a socket in the 95 lower end of the link *i*. A pair of links *m m'* connect the lower ends of links *i* and *j* and are provided with flanges *m'* overstanding the socket joint connection between toggle *k* and link *i* to hold the joint in position. Link 100 *m* is pivotally mounted on a pin *m''* which passes through the upper ends of the arms of the yoke *n*. Yoke *n* is carried by a pin *o'* on the vertically movable gate or head *o*.

This head *o* has guide grooves *o''* for the 105 head *h*. On the reverse side, the head *o* has a stud or projection *q* carrying the two toggles *r r*. The lower end of each toggle *r* carries a slide *r'* with an angle cutter or blade *r''*. Springs *s* are interposed between 110 the movable head or gate *o* and the main frame to counter-balance the weight of the

head and attached parts and to raise them to their normal inoperative position after the operation of shearing or punching has been completed.

- 5 The main frame carries the stationary cutters a^2 a^3 a^4 a^5 a^6 and die a^7 . The vertically movable head o carries the cutters o^3 o^4 and the punch o^5 . The cutters a^2 and o^3 constitute shears for dividing or shearing a plate. Preferably a channel or guide a^8 is provided on the main frame for one of the sheared edges and a table a^9 on the frame for the other sheared edge. The cutters r^2 and a^8 and r^2 and a^6 are adapted to cut reverse angles, the cutters o^4 a^4 and a^5 are adapted to cut rods or bars of any suitable shape.

When an operating lever c is pulled downward and outward, its link d draws the upper end of the arm e outward and thus turns the eccentric f' on the shaft f and forces the rod g downward, moves the slide h downward and the connecting links i and j downward, and the toggle k causes the links m to move downward and swing outward as the slide h descends, this swings the upper end of the yoke n outward and moves the main head or gate o downward with the shearing or punching cutters. A very long sweep of the operating lever c is thus translated into a relatively short throw of the head and cutters so as to enable a single operator to apply great power. When the operating lever is released, the springs s s returns the parts to their normal inoperative position. The connection between the arm e and the eccentric f' is such that when the rod e^2 is disengaged from the eccentric f' the movement of the eccentric in a counter-clockwise direction, as viewed in Fig. 1, may be effected without moving the corresponding arm e . This makes it possible to use either one of the operating levers c independently of the other. If it is desired to apply power by both of the operating levers c c , the rods e^2 will be engaged with their respective eccentrics f' and both levers operated at the same time, thereby obtaining double the amount of pressure. A very considerable advantage exists by reason of this double operating lever construction in that the machine can be operated from each side independently, or from both sides simultaneously thus getting the advantage of a right or left hand machine as well as the double power when desired.

The operating parts of the machine may be conveniently mounted on a turn-table having rollers t t so that the entire machine may be turned on the axis t' in the direction most convenient for the work at hand.

The same machine may be used as a belt-driven or motor-driven machine by removing the operating levers and the shaft f with eccentrics f' and rods g . The crank shaft u

is substituted for the shaft f and the connecting rod u' is substituted for the rod g as shown in Fig. 18. The frame v is mounted on the upper part of the main frame of the machine and supports the shafts u^1 u^2 u^3 and u^4 . These shafts carry respectively the gears v' v^2 v^3 v^4 v^5 and v^6 . The axis of the power shaft u^3 is preferably a prolongation of the axis of the pintle center t' of the turn-table, so that the gearing may be operated without interfering with the turning of the machine. w represents the fly-wheel or other motive power or device for rotating the gearing and operating the mechanism through the instrumentality of the slide h in the manner previously described.

What I claim is:—

1. In a machine of the character described, a supporting frame, a head slidably mounted in said frame, a slide movable relatively to said head, means for operating said slide, two sets of toggle links connected between the supporting frame and the slidable head and a pair of substantially parallel operating links connected between the slide and each set of toggle links.

2. In a machine of the character described, a supporting frame, a head slidably mounted in said frame, a slide movable relatively to said head and disposed between opposite sides of said head, toggle links at each of said opposite sides of the head connected between said head and the supporting frame and a pair of connecting links disposed at each side of the slide and extending from said slide to the toggle links at that side of the slide.

3. In a machine of the character described, the combination of a vertically movable head, a slide movable relatively thereto, a stationary member, an arm swinging on said stationary member, a yoke swinging on said head, a link connecting said slide and said arm, a second link connecting said slide and said yoke, means for connecting the ends of said links adjacent said yoke and said arm and means for operating the slide.

4. In a machine of the character described, the combination of a vertically movable head, a slide movable relatively thereto, a stationary member, an arm swinging on said stationary member, a yoke swinging on said head, a link connecting said slide and said arm, a second link connecting said slide and said yoke, means for connecting the ends of said links adjacent said yoke and said arm, means overlapping the joint between said arm and its link and means for operating the slide.

5. In a machine of the character described, the combination of a slide, a pivot rod transverse thereto, two eccentrics loosely mounted on said pivot rod, rods connecting said eccentrics with said slide, an arm for

- each eccentric and means of connection between each arm and its eccentric permitting the arm to move the eccentric and permitting the eccentric to move independently of the arm.
6. In a machine of the character described, a vertically movable head, a transversely pivoted member, toggle mechanism connecting said member and said head, an operating lever at each side of said machine and independently detachable means of connection between each operating lever and said member.
7. In a machine of the character described, a vertically movable slide, a transverse pivot rod, an eccentric mounted on said pivot rod, a rod connecting said eccentric and said slide, an arm having a hooked connection with said eccentric, a locking rod carried by said arm for engaging said eccentric, means for operating said rod and means for swinging said arm.
8. In a machine of the character described, a supporting frame, a vertically movable head on said frame, means for operating said head, a pair of toggle arms each pivoted at one end on said head, oppositely facing cutter slides on the frame, the opposite ends of said toggle arms being pivoted to the respective cutter slides and relatively stationary, oppositely facing, angular cutters cooperating with the cutter slides.
9. In a machine of the character described, the combination of a supporting frame, a head slidably mounted in said frame, a set of shearing cutters at one side of said head, punch and die members at the opposite side of said head, rod cutters adjacent the central portion of the head between the punch and shearing cutters at the opposite sides thereof, oppositely facing angular cutters mounted on the frame intermediate the punch and shearing cutters at the opposite sides of the head, and means on the head for operating said angular cutters.
10. In a machine of the character described, a vertically movable head, a slide vertically guided therein, a transverse shaft, a cap-piece extending over the top of said shaft and connecting the upper side portions of said slide, means of connection between said slide and said head, and means for operating said slide including a crank on said shaft and a rod connecting said crank and said slide.
11. In a machine of the character described, a supporting frame, a reciprocating tool carrying head working in said frame, an operating slide for said head, means for imparting movement to said slide, a pair of substantially parallel links pivoted at one end to said slide, a link pivotally connecting the opposite free ends of said substantially parallel links, and connecting links from said connected portions of the substantially parallel links to the supporting frame and the tool carrying head respectively.
12. In a machine of the character described, a supporting frame, a reciprocating tool carrying head working in said frame, an operating member relatively movable in respect to the head, means for imparting movement to said operating member, a pair of substantially parallel links connected at one end with said operating member, a link connecting the opposite free ends of said pair of links, and toggle links between said connected portions of the pair of links and the supporting frame and head.
13. In a machine of the character described, a supporting frame, a reciprocating tool carrying head working in said frame, an operating member movable relatively to said head, means for imparting movement to said operating member, a pair of links connected each at one end with the operating member, a link connecting the opposite free ends of said links, a toggle link engaged between said connecting link and the tool carrying head, and a second toggle link connected between one of the first mentioned pair of links and the supporting frame.
14. In a machine of the character described, a supporting frame, a reciprocating tool carrying head working in said frame, a slide movable relatively to the head, a toggle link pivoted at one end to the supporting frame, a link engaged with said toggle link at one end and engaged with the slide at its opposite end, a connecting link engaged with said operating link at a point adjacent the engagement of the toggle link therewith, a second operating link engaged with said connecting link at one end and with the slide at its opposite end and a second toggle link connected between said connecting link and the tool carrying head.
15. In a machine of the character described, a supporting frame, a reciprocating tool carrying head working in said frame, an operating slide disposed between opposite sides of the tool carrying head, means for imparting movement to said operating slide, a pair of operating links at each side of the slide and operatively connected therewith at one end, links connecting the opposite free ends of said operating links, toggle links engaged between said connecting links and the opposite sides of the head and toggle links connected between the frame and one of the operating links at each of said opposite sides of the head.
16. In combination, a supporting frame, a reciprocating tool carrying head working in said frame, a slide movable relatively to the head, means for operating said slide, a toggle link pivoted on the frame, an operating link having a socket in the end portion there-

- of receiving the free end of said toggle link, and connected at its opposite end with the slide, a second operating link connected with the slide, a link connecting said operating links and having a portion overlying the 5 socket in the first operating link to retain the end of the toggle link therein, and a second toggle link engaged between the connecting link and the head.
- 10 17. In combination, a supporting frame, a reciprocating tool carrying head working in said frame, an operating slide movable relatively to said head, means for imparting movement to said slide, compound toggle 15 connections between the supporting frame and the slide and the head, divergently operating cutters on the supporting frame and divergent toggles connected with the slide and working said cutters.
- 20 18. In a machine of the character described, the combination of a supporting frame, an operating slide, a pair of independently operable crank eccentrics pivotally supported on the frame, rods connecting 25 said crank eccentrics with the slide, an operating arm for each of the crank eccentrics, and means for independently connecting and disconnecting said operating arms to and from the respective crank eccentrics.
- 30 19. In a machine of the character described, a supporting frame, a slide working in said frame, a pair of independently operable crank eccentrics pivoted on the frame, rods connecting said crank eccentrics with 35 the slide, operating arms having hooked engagement with said crank eccentrics, and locking rods for releasably connecting said operating arms to the respective eccentrics.
- 20 20. In a machine of the character described, a supporting frame, a slide working in said frame, a pair of independently operable crank eccentrics pivoted on the frame 40
- and working to opposite sides of a common center, rods connecting said eccentrics with the slide and operating arms connected with the crank eccentrics and working in opposite 45 directions.
21. In a machine of the character described, a supporting frame, a slide working in said frame, a pair of independently operable crank eccentrics pivoted on the frame and working to opposite sides of a common center, rods connecting said eccentrics with the slide and operating arms connected with the crank eccentrics and working in opposite 50 directions, said operating arms having detachable means of connection with the respective crank eccentrics.
22. In a machine of the character described, a supporting frame, a slide working in said frame, a pair of independently operable crank eccentrics pivoted on the frame and working to opposite sides of a common center, rods connecting said eccentrics with the slide and operating arms connected with the crank eccentrics and working in opposite 55 directions, and operating handles at opposite sides of the machine connected with the operating arms and working in opposite directions.
23. In a machine of the character described, a supporting frame, a reciprocating tool carrying head working in said frame, a slide operable independently of said head, compound toggle connections between the 60 supporting frame, the slide and the head, independently operable handles, operating connections from said handles to the slide, and means for independently disengaging the connections from either of said handles 65 to the slide whereby one or both the handles may be employed at will.

CHARLES A. STICH.
